We claim the ornamental design for a mobile terminal housing, as shown and described.

DESCRIPTION

FIG. 1 is a perspective front view of a mobile terminal housing according to the present invention.

FIG. 2 is a front elevation view of the mobile terminal housing of FIG. 1.

FIG. 3 is a rear elevation view of the mobile terminal housing of FIG. 1.

FIG. 4 is a bottom view of the mobile terminal housing of FIG. 1.

FIG. 5 is a top view of the mobile terminal housing of FIG. 1.

FIG. 6 is a left side elevation view of the mobile terminal housing of FIG. 1; and,

FIG. 7 is a right side elevation view of the mobile terminal housing of FIG. 1.

The broken lines and unshaded portions contained within broken lines depict unclaimed features of the mobile terminal housing that form no part of the claimed design but are shown for purposes of illustration.
